UNITED STATES PATENT OFFICE.

JAMES D. BARNES, OF NASHVILLE, NORTH CAROLINA.

CLOTHES-CLAMP.

SPECIFICATION forming part of Letters Patent No. 781,930, dated February 7, 1905.

Application filed April 15, 1904. Serial No. 203,328.

To all whom it may concern:

Be it known that I, JAMES D. BARNES, a citizen of the United States, residing at Nashville, in the county of Nash and State of North Carolina, have invented certain new and useful Improvements in Clothes-Clamps, of which the following is a specification.

This invention relates to novel improvements in clamp devices particularly adapted 10 for use in securing clothes to clothes-lines.

The invention provides a peculiar form of clamping means consisting in its preferred adaptation of a supporting member having a plurality of clothes engaging or clamping 15 members formed therewith. The parts are specially arranged and afford a rigid means for attaching clothes as above mentioned.

For a full description of the invention and the merits thereof and also to acquire a knowledge 20 of the details of construction of the means for effecting the result reference is to be had to the following description and accompanying drawings.

While the essential and characteristic features 25 of the invention are susceptible of modification, still the preferred embodiment of the invention is illustrated in the accompanying drawings, in which —

Figure 1 is a perspective view showing the 30 supporting-loop having the clothes-line passed therethrough. Fig. 2 is a view in elevation, showing the manner of securing clothes and the disposition of the clamp device when the latter is independently mounted as regards 35 the line. Fig. 3 is a detail perspective view of the clamp device alone. Fig. 4 is a detail view of the modified form of the invention.

Corresponding and like parts are referred 40 to in the following description and indicated in all the views of the drawings by the same reference characters.

Referring to the drawings, the numeral 1 designates a clothes-line of any of the usual types in common use. The clamping device 45 which comprises my invention may be directly carried by the line, if desirable, or may be utilized entirely independent of the line to clamp clothes thereto in the contemplation of my invention. The above is advantageous in 50 that under certain conditions it is particularly

convenient to have the clamp devices arranged upon the line so that they may be instantly manipulated, so as to clamp the clothes which are to be hung from the said line. Again, it is often preferable that the clamp devices be 55 entirely free from the line, so that they may be readily removed whenever necessary.

Each of the clamp devices is composed of a supporting-loop 2, which virtually consists of a spring-coil of wire the end portions of which 60 are bent so as to form the spaced clamp members 3. The clamp members 3 are located upon the opposite sides of the main supporting-loop 2 and are located in relatively vertical positions in substantially the same plane 65 as the supporting-loop itself. The clamp members are formed by bending the wire from which the loop 2 is made downwardly, as shown at *a*, thence upwardly, as shown at *b*, and again downwardly, as shown at *c*, the portion *c* being projected at a right angle to the plane of the loop 2, representing the end of said wire. The extremity of each of the clamp members is upwardly turned and formed into an eye 4, so as to obviate the formation of 70 any projecting part which might engage in and tear the clothes which are secured to the line. The clamp members 3 are reversedly disposed, as most clearly shown in Fig. 3, and are adapted to positively engage the line 1 to 75 clamp the edge portions of the clothes thereto. The line 1 when the clamp device is in position is received and clamped between the parts *b* and *c* of each of the clamping members, which have a spring action in the co-operation 80 above mentioned. In Fig. 1 the clothes-line is shown passing through the main supporting-loop 2. When the device is used in this manner, it will be noted that as soon as the clothes are unclamped or released from engagement by the clamp device the latter will 85 be suspended from the line to remain in this position until again used. Fig. 2, however, illustrates the adaptation of the clamp device when used merely as an independent securing 90 means, in which case the coil of the loop 2 co-operates with the members 3 to clamp the clothes to the line.

The clamp device is made from spring-wire 95 which is of a suitable gage to lend the necessary 100

strength and rigidity and to give a spring action to the members 3. The loop 2 constitutes a member which readily admits of being grasped in manipulating the device preparatory to attaching clothes to the line 1 and in removing said clothes from the line.

- For supporting heavy goods, such as blankets or the like, it is very desirable that the clamp members be provided with the 10 spring-coils 5 at their upper portions, which latter would be integrally formed to lend a greater spring clamping action in the use of the device. The above structure is illustrated in Fig. 4 of the drawings, and it is further contemplated that the portion *c* of each of the 15 clamp members 3 may be crimped or corrugated to facilitate the binding or engaging action of the parts 3 in attaching clothes or the like in the manner above premised upon.
- 20 The clamping device being made from a single piece of wire of suitable length can be very cheaply manufactured, and this is a desideratum of no small importance.

Having thus described the invention, what is claimed as new is—

As an article of manufacture, a clothes-clamping device consisting of a single length of spring-wire bent intermediate its ends to form the main supporting and clamp loop 2, consisting of a spring clamping - coil, and 25 clamp members at opposite sides of the loop aforesaid, each of said clamp members being formed by the downwardly-bent end portion *a*, the upwardly-bent portion *b*, and the downwardly-bent extremity *c* projected from the 30 portion *b* at a right angle to the plane of the loop 2, the bent portions *c* and *b* of the clamp members being in spring engagement with each other.

In testimony whereof I affix my signature in 35 presence of two witnesses.

JAMES D. BARNES. [L. s.]
